HARRY DICKSON, OF CONGRESS PARK, ILLINOIS, ASSIGNOR TO IDEAL ROLLER & MANUFACTURING CO., INC., OF CHICAGO, ILLINOIS, A CORPORATION OF ILLINOIS.

PROCESS FOR MAKING BLANKETS FOR PRINTING MACHINES.

Application filed June 19, 1926. Serial No. 117,025.

This invention relates to a process for making blankets for printing machines and relates particularly to a process for producing a blanket for offset presses, newspaper presses and the like, said blanket being preferably composed of a tough, flexible backing member having a face layer of a soft resilient material.

Heretofore, blankets for the purpose of offsetting in offset lithography, for backing the paper to be printed in newspaper presses, and for similar uses in various types of printing machinery, have been made of rubber reenforced with a backing of woven fabric. The use of rubber in any printing machinery has a great many disadvantages, one of which resides in the fact that oils used in the printing ink cause a deterioration of the rubber. Also, the oil used for lubricating the bearings of cylinders, rollers, and other rotatable or movable members, frequently works its way onto the rubber blanket and likewise causes a deterioration in the blanket. Moreover, the wide range of temperatures encountered in a printing room affects the rubber blanket and causes it to become unduly hardened or softened and frequently causes a swelling or shrinking of the blanket, whereby, for example, should the blanket be used for transferring subject matter on paper a distortion of such matter would result because of interference with the proper registering of the subject matter upon the paper.

It has been found, as is well known in the art, that rollers used on printing presses, typewriting machines, and other similar devices, may be made of vulcanized oil, or, an ordinary roller composition, which latter consists mainly of glue, glycerine and water, and that neither of these materials is appreciably affected by oils or temperature conditions. However, it is difficult to cast a layer of these resilient materials on a flexible backing member so that it is of a uniform thickness and also in such manner that it properly adheres to the backing member.

Further, in the casting of such substances it is practically impossible to eliminate air or gas cells which are usually present in the material, or if not present, are formed by the casting or mixing process.

As has been pointed out, the use of a

rubber blanket is highly impracticable for the reasons mentioned, and it is therefore one of the objects of this invention to provide a process for making a blanket comprising a tough flexible backing member having a face layer of a soft resilient material which is not appreciably affected by printing inks, lubricating oils or temperature conditions.

It is a further object of this invention to provide a process for evenly distributing the soft resilient material over the surface of the backing member and holding said soft resilient material in this evenly distributed manner until it becomes solid.

A still further object of this invention is to provide a process which will eliminate air or gas cells which may be present in the material or which may have formed during the casting or mixing process.

Further objects of this invention will be apparent from the description and drawings forming a part of this specification to which reference may now be had for a more complete understanding of the characteristic features of this invention, in which drawings:

Figure 1 is an axial section of a mold in a centrifugal machine prior to the operation of applying the soft resilient material to the backing member;

Fig. 2 is a sectional view through the mold taken on the line 2—2 of Fig. 1;

Fig. 3 is a sectional view similar to that of Fig. 2 showing the application of the soft resilient material to the backing member; and

Fig. 4 is a sectional view similar to that of Fig. 3 showing the blanket reversed and in use as an offsetting blanket.

Referring more particularly to the drawings, a centrifugal casting machine 10 is shown comprising a bed 11 and head and tail stocks 12 and 13 respectively. The tail stock is adjustable longitudinally of the bed and is locked to the bed by a hand screw 14.

A cylindrical rotative shell-mold 15, having preferably a thin layer of wax 15^a, on the inner surface thereof is supported at its ends by conical centering members 16, 17, the mold being provided with friction rings 18 and 19 that bear directly against the inner faces of said conical centering members. The centering member 16 is fixed

to a rotative drive shaft 20 which is mounted in suitable bearings 21 of the head stock. Power is transmitted to said shaft 20 to rotate the mold by any suitable means as for example a pulley 22.

The opposite conical centering and supporting member 17 is supported through a suitable anti-friction bearing 27 on the tail stock 18 so as to rotate freely with respect to said tail stock. The member 17 is provided with an apical opening through which a feed tube 28 extends, said tube being in communication with the outlet end of a funnel 29 that is supported on the tail stock, and through which funnel the materials are poured into the mold.

In the process of producing a blanket of the class heretofore described, a tough flexible backing member 30 is positioned within the shell mold 15 and held snugly against the inner coaxial surface thereof by means of an adjustable clamping member 31 disposed at each end. The clamping members 31 may be formed of two semi-circular disc members held in the desired relation with each other by means of a pair of metal strips 32 on each side thereof and fastened by bolts 33 extending therethrough and engaging slots 34 in said discs.

After the mold 15 containing the backing material 30 has been assembled in the centrifugal machine 10 between the conical centering and supporting members 16 and 17, the machine is set in motion and a quantity of the soft resilient material in a liquid state, which has been accurately measured to produce a layer 35 of desired thickness, is poured through the funnel 29 into the rotating mold, and centrifugal force is developed by the rotation of the mold which causes the material to form against the backing member and produce a layer 35 of uniform thickness. Within a few minutes after being introduced into the mold and while being held in a layer of uniform thickness against the backing member, the soft resilient material becomes solid. This centrifugal force also functions to draw to the inside of the material, and eliminate therefrom any air or gas cells which may be present therein.

After the material has firmly set, the machine is stopped and the mold is removed, as shown in Fig. 3 of the drawings. In case the mold is lined with a thin layer of wax 15^a, the mold is subjected to heat to melt the wax and the blanket is easily removed by releasing the clamping members. Due to the elasticity of the material of the blanket, the wax is not an essential element of this process although it is desirable since it serves to remove the blanket more readily from the mold.

Inasmuch as the backing member is flexible and the soft resilient material formed on the backing member is elastic, the blanket

may be readily reversed, for example, in centrifuging the soft resilient material on the backing member within the mold, the backing member is outermost, whereas, upon removal from the mold, the blanket may reverse its curvature in order that the soft resilient material may be outermost.

If desired, the layer 35 may be subjected to any machining operation, such as grinding or cutting, either when laid flat or when the curvature of the blanket is reversed and placed on a revolving cylinder on a mandrel. As it is preferable to have a margin 36 along the edges of the backing member 30, which margin is not covered with the soft resilient material 35, this margin may be produced by any preferred method for removing the resilient material at this time.

As shown in Fig. 4 of the drawings, the blanket now consisting of a flexible backing member 30 having a layer of soft resilient material 35 thereon, is fastened to a cylinder 37 of an offset press by means of bolts 38 projecting through the margin 36 onto the backing member 30 and into the cylinder, said blanket being reversed from its position in the mold and having the soft resilient material 35 outermost.

Hereinbefore it has been stated that the use of a rubber blanket is highly impracticable, but that the use of an ordinary roller composition consisting mainly of glue, glycerine and water or, that the use of vulcanized oil, would eliminate the undesirable qualities found in a rubber blanket. In the preparation of these two last named substances for use in the mold, practically the same conditions exist inasmuch as they are both primarily in a liquid state and are thereafter solidified. In the use of an ordinary roller composition, the material is poured into the mold in a melted condition and allowed to cool and thereby become solid while the mold is rotating. In the vulcanizing of oil, a mixture of vegetable oil and sulphur chloride in proper proportions is poured in a liquid state into the mold which mixture, by means of a chemical reaction, becomes solid within a few minutes after being introduced into the mold and while the mold is being rotated. Since the vulcanizing oil or the aforementioned roller composition lacks the tenacity, strength, and toughness which the rubber contains, it is preferable to use a backing member of metal. This metal backing may be of zinc, brass, aluminum or any other sheet metal having flexibility at the degree of thickness required. It is preferable to employ a thickness of approximately 10/1000 of an inch in the metal backing member, while the thickness of the vulcanized oil may approximate 55/1000 of an inch which is the customary thickness for blankets of offset presses. It is to be understood that this invention is not to be limited to a process for produc-

ing a blanket of the dimensions herein specified inasmuch as various blankets used in connection with printing machines and the like may have blankets of different thickness 5 and, as has been stated, the material is accurately measured to produce a layer of any desired thickness. All dimensions are given for illustrative purposes.

Although it is considered preferable to 10 employ a flexible metal backing member, it may be desirable to use woven fabric in some instances. In such case, the fabric may be treated in any convenient manner in order to obtain the necessary qualities and adherence, or it might be desirable to use several layers of fabric. In any event, the process of forming the blanket by means of a centrifugal method of producing the soft resilient material on a tough flexible backing 20 member and reversing the blanket upon removal from the roll so as to meet its various uses, would not vary.

While this invention has been described with relation to a particular method, it is to 25 be understood that the same is not to be limited except in accordance with the appended claims and the prior art.

I claim:—

1. The process of making a blanket for 30 printing presses and the like which comprises applying by centrifugal action a liquid material to a flexible backing member held against the curved surface of a mold, said centrifugal action holding said liquid 35 material to said backing member during solidification, then withdrawing the blanket from said mold and finally reversing the curvature of said blanket.

2. The process of making a blanket for

printing presses and the like which com- 40 prises applying by centrifugal force a layer of soft resilient material to the inner surface of a flexible backing member held against the curved surface of a mold, then withdrawing the blanket from said mold and finally 45 reversing the curvature of said blanket.

3. The process of making a blanket for printing presses and the like which comprises applying by centrifugal action a liquid material to a flexible backing material held 50 against the curved surface of a mold and simultaneously eliminating air and gas cells therefrom while in a liquid or semi-liquid form, then withdrawing the blanket from said mold and finally reversing the curvature 55 of said blanket.

4. The process of making a blanket for printing presses and the like which com- 60 prises applying by centrifugal action a layer of resilient material to a flexible backing member held against the curved surface of a mold having a lining material of a lower fusing point than that of the other material, then heating said lining material to withdraw the blanket from the mold, and finally 65 reversing the curvature of said blanket.

5. The process of making a blanket for printing presses and the like which comprises applying by centrifugal action a layer of resilient material to a flexible backing member 70 held against the curved surface of a mold, and withdrawing the blanket from said mold and finally reversing the curvature of said blanket to tool or grind the same on a mandrel to a desired thickness. 75

In witness whereof, I have hereunto subscribed my name.

HARRY DICKSON.
